DESIGN FOR A COOKING STOVE

Bertrand B. Kahn, Cincinnati, Ohio, assignor to The Estate Stove Company, Hamilton, Ohio, a corporation of Ohio

Application June 17, 1933, Serial No. 48,428

Term of patent 7 years

To all whom it may concern:

Be it known that I, BERTRAND B. KAHN, a citizen of the United States of America, residing at Cincinnati, in the county of Hamilton, State of Ohio,
have invented a new, original, and ornamental Design for Cooking Stoves, of which the following is the specification, reference being had to the accompanying drawing, forming a part thereof.

Figure 1 is a perspective view of the stove showing my new design.

Fig. 2 is a vertical section on the lines 2—2 of
Fig. 1.

The drawing is shaded to show contrasting color effect and the beading around the stove top is of a bright polished metal.

I claim:

The ornamental design for a cooking stove substantially as shown, and described.

BERTRAND B. KAHN.
